UNITED STATES PATENT OFFICE.

CONSTANT BOUILLON, OF TORRINGTON, CONNECTICUT, ASSIGNOR TO THE HENDEY MACHINE COMPANY, A CORPORATION OF CONNECTICUT.

MECHANISM FOR RELIEVING THE TEETH OF CUTTERS.

1,132,551.

Specification of Letters Patent. Patented Mar. 23, 1915.

Application filed June 26, 1911. Serial No. 635,248.

To all whom it may concern:

Be it known that I, CONSTANT BOUILLON, a citizen of the United States, residing at Torrington, in the county of Litchfield and 5 State of Connecticut, have invented a new and useful Mechanism for Relieving the Teeth of Cutters, of which the following is a specification.

The object of this invention is to provide 10 a new and improved mechanism for relieving or backing off the teeth of taps, dies, hobs, reamers, milling cutters, etc. Cutters of this character require that the teeth shall be backed off behind their cutting edges to 15 relieve the same from contact with the material upon which said cutters are designed to work. These cutters are generally turned in a lathe and it has been heretofore proposed to provide the lathe with an attachment 20 so that this backing off operation can be performed.

My invention, while applicable to any mechanism that may be employed to back off the teeth of cutters of the character described, 25 has been specifically designed as an improvement in the said attachment for lathes.

The particular objects of the invention are to provide an improved mechanism of 30 this character which will be efficient in operation; which will allow the lathe to be run in a reverse direction easily and without noise or jar; and to provide a mechanism by which the backing off action of the tool can be adjusted very finely.

Several specific embodiments of the invention are illustrated in the accompanying four sheets of drawings, referring to which,

Figure 1 is a front elevation of an engine 40 lathe with my attachment applied thereto. Fig. 2 is a plan of the attachment on enlarged scale. Fig. 3 is an end elevation of the change gearing employed for operating the attachment. Fig. 4 is a side elevation 45 and Fig. 5 an end elevation of the operating crank pin. Figs. 5^a and 5^b are diagrams illustrating different adjustments of the crank pin. Fig. 6 is a detail view of the operating cam and connections. Fig. 7 is a 50 side elevation of the mechanism for adjusting the relative position of the crank pin. Fig. 8 is an elevation of the operating shaft and parts carried thereby. Fig. 9 is an end view of the pawl and ratchet mechanism. 55 Fig. 10 is a plan view of the same. Fig. 11

is a side elevation of the ratchet. Fig. 12 is a view similar to Fig. 9 illustrating the parts in a different position. Fig. 13 is an end elevation of a cutter indicating how the teeth are backed off. Fig. 14 is a side elevation of a modified form of adjusting mechanism. Fig. 15 is a side elevation of the parts shown in Fig. 14. Fig. 16 is a detail of the mechanism shown in Figs. 14 and 15. Fig. 17 is a side elevation of a modified cam connection, and Fig. 18 is a side elevation of the mechanism illustrated in Fig. 17.

Referring first to the preferred form of mechanism which is shown in the first three sheets of the drawings, A designates an engine lathe of any ordinary or approved construction which has the usual headstock, tool carriage, tail-stock, and operating parts. On the carriage is adjustably mounted a tool block B, which can be moved relatively 70 to the work by the ordinary adjusting handle and screw. Fitted to slide in ways formed on top of the tool block B is a tool carrier C which has a tool post D adjustably secured thereon and in which the cutting tool E is secured. By this arrangement, the tool can be adjusted relatively to the work and the tool carrier C can slide on the tool block B for the purpose of backing off, 75 as hereinafter described.

Secured on the lathe bed in suitable relation to the head-stock is a bracket 10 (Fig. 2) in which is journaled a sleeve 11, which sleeve is held in place by a nut 12. On the projecting end of the sleeve is hung a sweep 80 arm 13 which carries two intermediate gears 14 and 15 which are mounted on studs which can be adjusted in slots cut in the sweep arm 13. These parts are positioned so that the intermediate gear 15 can be engaged 85 with a pinion 160 which is detachably secured on the projecting end of the feed or gear shaft in the head-stock. The sweep 13 is provided with an extension 16 which bears against the extension 17 of the bracket 10, and a stud 18 having a nut 180 is arranged 90 between these extensions so that the sweep can be locked in adjusted position.

A shaft 19, which I will term the operating shaft, is journaled in the sleeve 11 and 95 a gear or pinion 20 is detachably secured on the end of the operating shaft 19.

The gearing thus far described constitutes a change gearing by which the operating shaft can be rotated by power from the 110

head-stock at different speeds, depending on the size and adjustments of the change gearing.

A casing 21 is formed on the end of the sleeve 11 and a plate 22 is secured to the face thereof. Pins 23—23 (Figs. 9 and 12) project from the inside of the casing and pivotally mounted on the same are pawls 24—24, which are normally pressed inward by means of springs 25—25 secured on the outside of the casing and extending in through slots cut therein. A ratchet wheel 26 is keyed on the end of the operating shaft 19 and held in place thereon by a nut 27 which is threaded on the shaft 19 and which may be kept in adjusted position by a screw 28. The ratchet wheel 26 has a collar or hub 29 (Fig. 11) on one side which fits inside of the plate 22 and a collar or hub 30 on its other side which is employed for the purpose hereinafter specified. The pawls 24—24 are provided with pins 31—31, on which are hung shoes or struts 32—32 which have their inner ends shaped, as shown, to engage the smooth collar or hub 30 on the ratchet wheel 26. The operation of this pawl and ratchet mechanism is as follows:—When the ratchet wheel is turned in the direction to engage the pawls, the shoes or struts 32—32 swing out idly, as shown in Fig. 9; but when the ratchet wheel is turned in the other direction, so as not to drive the pawls 24—24, the ends of the struts will engage the smooth collar 30 and will lift the pawls so that they will not be engaged by the teeth of the ratchet wheel 26, as illustrated in Fig. 12. The bearing of the ends of the struts on the hub or collar 30 is nearly all on one side of the line of pressure, and so long as the ratchet wheel is run backward, as shown in Fig. 12, the struts will remain in place and hold the pawls 24—24 away from the ratchet wheel 26. But when the motion is reversed, the struts will fall and the pawls will again engage the ratchet. The casing 21 is provided with pins 33—33 to control the motion of the struts and guide them to the position shown in Fig. 12. By this arrangement, the objectionable click and noise when the ratchet wheel is running backward is avoided. The gearing is so arranged that the ratchet wheel turns in the direction indicated in Fig. 9 when the work is being turned in the proper direction for the backing off action or engagement of the tool.

A cam 35 is keyed on the end of the sleeve 11 and therefore the sleeve and cam turn when the ratchet wheel turns in the direction shown in Fig. 9 and engages the pawls. Preferably the ratchet wheel 26 and the cam 35 are given the same number of projections.

The bracket 10 is provided with a bearing 36 (Figs. 2, 6 and 7) and journaled in the same is a shaft 37 secured on which, at one

side of the bearing, is a clutch or toothed ring 38. A cam lever 39 is loosely mounted on the end of the shaft 37 and held in place thereon by a nut and washer 40. This cam lever is provided on its face with a clutch or toothed ring 41 shaped to engage the clutch or toothed ring 38. By this arrangement, by loosening the nut and washer 40, the angular position of the shaft 37 relatively to the cam lever 39 can be adjusted very minutely; and if desired, the clutch rings may be provided with indicating marks for determining the degree of adjustment. The cam lever 39 is provided at its lower end with a cam shoe 42 which engages the cam 35. This cam shoe may have a stud 43 which extends through the cam lever 39 and is held in position therein by a nut 44. The upper end of the cam lever 39 is forked as at 45 and these forks engage a plunger 46 between a collar 47 formed on a bushing 48 loosely fitted thereon and nuts and washers 49 adjustably secured on the end of the plunger. The plunger works in a bearing 50 formed in the bracket 10, and a spring 51 is housed in said bearing and engages the end of the bushing 48 normally to force the upper end of the cam lever to the right, as shown in Fig. 6. A nut 52 is threaded on the end of the plunger 46 to limit the outward movement of the plunger. By this arrangement, an oscillating movement will be imparted to the shaft 37 by the cam 35.

The outer end of the shaft 37 carries one member 53 (Fig. 2) of a universal joint, pivoted to the block of which is the other member 54 which carries a tube 55 which has a square opening therein. Telescoping in said tube is a square shaft 56 which carries one member 57 of another universal joint, the other member 58 of which is pivoted to the block thereof and is secured on the end of a shaft 59 journaled in bearings 60—60 formed on the tool block B. The tool carrier C has a shield secured thereto which covers said bearings and contiguous parts.

The shaft 59 is cut away as at 61, as illustrated in Fig. 4, and eccentrically fitted into the end of said shaft 59 is a pin 62 which thus forms a crank-pin. This crank-pin is connected by a link 63 to a pin 64 secured in the tool carrier C. By this arrangement, the angular motion transmitted from the cam 35 will be utilized to move the tool carrier and thus the tool inwardly and outwardly relatively to the work or cutter operated upon. This will provide for the necessary backing off of the teeth.

In Fig. 1 of the drawings a tap is shown as being backed off and in Fig. 13 the end of this tap is shown and the necessary backing off of the teeth is indicated by the reference letter F. The operation is as follows:—The cutter, which it is desired to back off, is first

turned to shape, threaded if it is to form a tap, and then is fluted or grooved. The cutter is then placed between the centers of the lathe and connected by any of the ordinary 5 dogs to turn with the live spindle of the head-stock. The change gearing by which the attachment is driven is adjusted and set so that the tool will be given the necessary number of movements to correspond with 10 the fluting of the cutter. If the cutter has straight flutes thereon this number of movements per revolution will correspond to the number of grooves, but if the flutes are cut spirally, the proper lead will be obtained by 15 a proper adjustment of the gearing. The feed or lead screw of the lathe is then caused to move the carriage toward the head-stock as the work is rotated. As the tool engages the cutter it will move inwardly and out- 20 wardly in proper time relation therewith to back off the teeth properly. On the return movement of the carriage, if it is necessary to run the lathe backward for this purpose, the ratchet wheel will not engage the pawls 25 and the operating cam will remain out of operation so that the in-and-out movement of the tool will not take place during the return of the carriage. This return will be accomplished noiselessly, by reason of the 30 automatic disengagement of the pawls from the ratchet wheel previously described. The amount and direction of the inward travel of the tool can be decided by adjusting the clutch rings, as previously described, 35 to vary the position of the shaft 37 relatively to the cam lever so that the oscillation of the crank-pin 62 takes place at different angles. For illustration, in Fig. 5^a the position of the cam lever is adjusted so as to 40 get a small backing off movement of the tool, while in Fig. 5^b a different adjustment is arranged which will provide for a larger in-and-out movement of the tool.

In Figs. 14, 15 and 16 a modified mechanism for adjusting the movement of the tool is shown. In this arrangement, the cam lever 39 is secured on an independent shaft 65 journaled in a bearing 66 formed on the bracket 10. On the end of this independent 50 shaft is secured a forked lever 67. A slotted lever 660 is secured on the end of the shaft 37 and adjustably secured in said lever is a stud 670 which can be held in position by a nut 68. The stud 660 carries a roll 69 which 55 engages the forked lever 67. By adjusting the position of the stud 670 in the slotted lever 660, the amount of oscillation imparted to the shaft 37 can be varied and hence the backing off movement of the tool can be 60 adjusted.

In Figs. 17 and 18 a modified arrangement is shown for allowing the cam to turn backwardly without operating the cam lever. In this modification, the cam lever 66 is forked at its lower end and a cam shoe 70

is hinged thereto by means of a pin 71. The cam shoe is held in position, shown in full lines in Fig. 17, by a spring 72 engaging a pin 73 projecting from the cam shoe, the other end of which spring is secured to the hub of the cam lever. By this arrangement, when the cam turns in a direction indicated by the arrow, the cam lever will be oscillated, but when the motion is reversed, the hinged cam shoe will fold upwardly and 75 will allow the steep portions of the cam to pass the same without oscillating the cam lever. In this modification the ratchet wheel and pawls are not employed.

Many other modified mechanisms may be 80 devised for practising my invention without departing from the scope thereof as expressed in the claims.

Having thus fully described my invention, what I claim and desire to secure by 85 Letters-Patent is:—

1. In a mechanism for relieving or backing off the teeth of cutters, the combination of a tool carrier, means for moving the same forward and backward, mechanism for reciprocating the tool carrier during its cutting movement, and connections in said mechanism arranged so that the same will be inoperative to reciprocate the tool carrier when said mechanism is run in a reverse 90 direction. 95

2. In a device of the class described, the combination of a sliding tool carrier, mechanism for reciprocating the tool carrier during its cutting movement, including 100 a pawl and ratchet, and means arranged to throw the pawl out of operation automatically when the mechanism is run in a reverse direction, thereby preventing reciprocation of said tool carrier. 105

3. In a device of the class described, the combination of a sliding tool carrier, mechanism for reciprocating the tool carrier during its cutting movement, and means for automatically rendering said mechanism at 110 times inoperative, said means including a ratchet wheel and a pawl, a hub on the ratchet wheel, and a strut pivoted to the pawl and mounted to throw the pawl out of operation automatically when the mechanism is run in a reverse direction. 115

4. In a machine for relieving the teeth of cutters, the combination of a tool carrier, mechanism for reciprocating said carrier toward and from the work, driving means for said mechanism, and a device in said mechanism effective to render the mechanism automatically inoperative when the driving means is run in the reverse direction. 120

5. In a mechanism for relieving the teeth of cutters, the combination of a sliding tool carrier, means for reciprocating the same during its cutting movement, means for driving said mechanism, including a transmitting device which is continuously ro- 125 130

- tated in locked engagement during the cutting movement, and means arranged to throw the device out of operation automatically when the driving means is run in the reverse direction for the return of the tool carrier.
6. In a mechanism of the class described, the combination of a sliding tool carrier, means for reciprocating the same during its cutting movement, a mechanism for operating said means, and means for automatically rendering said mechanism at times inoperative, said means including a driven ratchet wheel arranged to turn continuously during the cutting movement, a pawl engaging said ratchet wheel, and means arranged to throw the pawl out of operation automatically when the ratchet wheel is run in a reverse direction for the return movement of the sliding tool carrier.
7. In a mechanism of the class described, the combination of a sliding tool carrier, a shaft connected to reciprocate the tool carrier, an operating cam, and a cam lever adjustably mounted on said shaft, relative adjustment of said lever and shaft being effective to substantially vary the extent of the reciprocatory movement of the sliding tool carrier.
8. In a mechanism of the class described, the combination of a sliding tool carrier, a shaft connected to reciprocate the same, a clutch ring on the shaft, a cam lever mounted on the shaft and having a clutch ring for engaging the clutch ring fast on the shaft, means for adjustably securing said clutch rings together whereby the shaft and cam lever may be secured together in different adjusted positions, and an operating cam.
9. In a mechanism of the class described, the combination of a tool block, a tool carrier fitted to slide thereon, a crank-pin connected by a link to the tool carrier, said crank-pin being mounted on a shaft journaled in bearings carried by the tool block, means for oscillating said shaft, and means

for adjusting the angular position of said oscillation, whereby the movement of the tool carrier can be varied.

10. In a mechanism of the class described, the combination of a tool block, a tool carrier fitted to slide thereon, a shaft mounted in bearings on the tool block and carrying a crank-pin connected by a link to the tool carrier, a telescoping connection to said shaft including universal joints, an operating cam, a cam lever engaging the same, and means for adjusting the angular position of the crank-pin relatively to the cam lever.

11. In a device of the character described, the combination of a tool block, a tool carrier sliding thereon, an operating shaft, change gearing for driving the same, a ratchet carried by said shaft, a sleeve surrounding said shaft and carrying pawls, engaging said ratchet, a cam mounted on said sleeve, a pivoted cam lever engaging said cam, a shaft to which said cam lever is adjustably connected, a shaft mounted in the tool block, telescoping and universal connections between said shafts, and a crank-pin carried by said second shaft and connected by a link to the tool carrier.

12. In a mechanism of the class described, the combination of a sliding tool carrier, a shaft connected to reciprocate the same, a slotted lever on the shaft, a cam lever mounted to swing on an axis at one side of the shaft, a forked lever fixed with respect to the cam lever and crossing said slotted lever, means for securing the forked and slotted levers together in different adjusted positions, and an operating cam for the cam lever.

In testimony whereof I have hereunto set my hand, in the presence of two subscribing witnesses.

CONSTANT BOUILLON.
